(57) **CLAIM**

The ornamental design for a wood guardrail for roadways, as shown and described.

DESCRIPTION

FIG. 1 is a top and front perspective view of a wood guardrail for roadways showing my new design;

FIG. 2 is a left end view of FIG. 1;

FIG. 3 is a front elevational view of FIG. 1;

FIG. 4 is a rear elevational view of FIG. 1; and,

FIG. 5 is a cross-sectional view taken along line 5—5 of FIG. 3.

The right end view of FIG. 1 is identical to the left end view shown in FIG. 2.

The bottom view of FIG. 1 is identical to the top view.

The claimed design is broken in the center indicating indefinite length.
